UNITED STATES PATENT OFFICE.

ISAAC S. KEELER, OF GRAND RAPIDS, MICHIGAN, ASSIGNOR TO KEELER BRASS COMPANY, OF GRAND RAPIDS, MICHIGAN.

LATCH.

Application filed November 17, 1924. Serial No. 750,372.

To all whom it may concern:

Be it known that I, ISAAC S. KEELER, citizen of the United States, residing at Grand Rapids, county of Kent, State of Michigan, have invented certain new and useful Improvements in Latches, of which the following is a specification.

This invention relates to improvements in latches.

10 The main object of this invention is to provide an improved latch which is particularly adapted for use on refrigerators and one exerting a clamping action on the door when the latch is engaged.

15 A further object is to provide an improved latch in which the bolt is automatically held in retracted position to be released on the closing of the door and thereby avoiding noise and friction in the engagement of 20 the bolt with the keeper.

Objects pertaining to details and economies of my invention will definitely appear from the detailed description to follow.

I accomplish the objects of my invention 25 by the devices and means described in the following specification. The invention is clearly defined and pointed out in the claims.

A structure embodying the features of 30 my invention is clearly illustrated in the accompanying drawing forming a part of this application, in which:

Fig. I is a top plan view of a latch applied to a door, fragments only of the door and its casing being indicated and the door being 35 shown in completely closed position.

Fig. II is an inverted view of the latch.

Fig. III is a detail view partially in section on a line corresponding to line 3—3 of Fig. II, looking in the direction of the 40 arrows, fragments of the door and casing being shown as in Fig. I and the door being shown in partially closed position.

Similar numerals of reference indicate similar parts in all of the views.

45 Referring to the drawing, 1 represents a door and 2 the casing of a refrigerator or like structure to which I have shown my improved latch applied.

My improved latch comprises a housing 50 3 having side flanges 4 provided with holes 5 adapted to receive the attaching screws. This housing has outwardly projecting pivot ears 6 on the top thereof spaced to receive the lever 7 which is mounted on the pivot 55 8 carried by the ears. This lever projects

through the opening 9 on the top of the housing.

The housing has opposed openings 10 and 11 in its end walls adapted to reciprocatingly support the bolt 12. This bolt is 60 shouldered at 13, a coiled spring 14 being arranged on the bolt to engage this shoulder with its outer end engaging the housing so that the bolt is projected by the spring.

Adjacent its forward end the bolt is provided with a catch shoulder 15 adapted to engage the end of the housing when the bolt is retracted as shown in Fig. III holding the bolt in its retracted position. The bolt is retracted by means of the lever 7, 70 16 of the lever engaging the slot 17 of the bolt.

The rear end of this slot is outwardly and rearwardly inclined so that as the lever forces the bolt backwardly against the tension of the spring, an inward pressure is applied to the bolt to cause its catch to swing into engagement.

The coacting strike 18 is provided with a tappet lug 19 disposed in a plane in front 80 of the keeper 20 of the strike. The bolt has an inwardly projecting finger 21 which engages this lug 19 as the door is swung to its closed position as shown in Fig. II, thereby disengaging the bolt catch and allowing the projection of the bolt by its spring. The face of the keeper is inclined so that the bolt engaging this inclined surface exerts a camming action on the bolt, thus forcing the door into its casing. 90

As the door swings to closed position, the bolt does not engage the inclined surface 22 of the strike as is usual in latches of this type, owing to the bolt being held in its retracted position. This avoids friction and 95 noise and permits the use of a strong spring for projecting the bolt into engagement with the strike, and, owing to the camming action, as stated, forcing the door into its seat.

Having thus described my invention what 100 I claim as new and desire to secure by Letters Patent is:

1. In a latch, the combination of a housing having an opening in the top thereof, the end walls of the housing being provided 105 with opposed bolt openings, a bolt reciprocatingly mounted on said bolt openings and having an inwardly projecting finger at its front end and a shoulder like catch on its inner side engageable with the front end of 110

the housing when the bolt is retracted, said bolt having a slot therein alined with said opening in said housing, a spring for projecting said bolt arranged within said housing, a retracting lever pivotally mounted on said housing and having an arm projecting through said opening in said housing into engagement with said slot in said bolt, the rear wall of the slot being rearwardly inclined so that when the bolt is retracted its front end swings inwardly to engage its said catch, and a strike having a projection disposed in a plane in front of its keeper and with which said finger on said bolt engages on the closing of the door to disengage the bolt catch.

2. In a latch, the combination of a housing having an opening in the top thereof, the end walls of the housing being provided with opposed bolt openings, a bolt reciprocatingly mounted in said bolt openings and having an inwardly projecting finger at its front end and a shoulder-like catch on its inner side engageable with the front end of the housing when the bolt is retracted, said bolt having a slot therein alined with said opening in said housing, a spring for projecting said bolt arranged within said housing, a retracting lever pivotally mounted on said housing and having an arm projecting through said opening in said housing into engagement with said slot in said bolt and coacting with said spring to swing the bolt laterally to catch engaging position when the bolt is retracted, and a strike having a projection disposed in a plane in front of its keeper and with which said finger on said bolt engages on the closing of the door to disengage the bolt catch.

3. In a latch, the combination of a housing, a bolt reciprocatingly mounted on said housing and having an inwardly projecting finger at its front end and a catch on its inner side engageable when the bolt is retracted, a spring for projecting said bolt,

45

a retracting lever pivotally mounted on said housing and having an arm projecting into said housing into engagement with said bolt, the bolt having an inclined surface with which the lever coacts so that when the bolt is retracted its front end swings inwardly to engage its said catch, and a strike having a projection disposed in a plane in front of its keeper and with which said finger on said bolt engages on the closing of the door to disengage the bolt catch.

4. In a latch, the combination of a housing, a bolt reciprocatingly mounted on said housing and having an inwardly projecting finger at its front end and a catch on its inner side engageable when the bolt is retracted, a spring for projecting said bolt, a retracting lever pivotally mounted on said housing and having an arm projecting into said housing into engagement with said bolt and coacting with said spring to swing the bolt laterally to catch engaging position when the bolt is retracted, and a strike having a projection disposed in a plane in front of its keeper and with which said finger on said bolt engages on the closing of the door to disengage the bolt catch.

5. In a latch, the combination of a housing, a bolt reciprocatingly mounted in said housing and having a catch on its inner side engageable when the bolt is retracted, a spring for projecting said bolt, a retracting lever pivotally mounted on said housing and having an arm projecting into said housing into engagement with said bolt, the bolt having an inclined surface with which the lever coacts so that when the bolt is retracted its front end swings inwardly to engage its said catch, and a strike having a part disposed in a plane in front of its keeper and with which said bolt engages on the closing of the door to disengage the bolt catch.

In witness whereof I have hereunto set my hand.

ISAAC S. KEELER.
